HACK SAW

Raymond C. Dreier, Chicago, Ill.

Application October 29, 1959, Serial No. 58,116

Term of patent 14 years

(Cl. D93—4)

Fig. 1 is a side view of a hack saw embodying my new design;

Fig. 2 is a top view thereof; and

Fig. 3 is an end view of a hack saw as seen from the right in Fig. 1.

The side not shown is substantially the same as the side shown.

I claim:

The ornamental design for a hack saw, substantially as shown and described.
